(57) **CLAIM**

The ornamental design for left and right motorcycle mirror guards as shown and described.

DESCRIPTION

FIG. 1 is a top, front perspective view illustrating a left motorcycle mirror guard of my design for left and right motorcycle mirror guards.

FIG. 2 is a bottom, front perspective view thereof.

FIG. 3 is a front view thereof.

FIG. 4 is a rear view thereof.

FIG. 5 is a right-side view thereof.

FIG. 6 is a left-side view thereof.

FIG. 7 is a top view thereof.

FIG. 8 is a bottom view thereof.

FIG. 9 is a perspective view thereof mounted on a left motorcycle mirror.

FIG. 10 is a top, front perspective view illustrating a right motorcycle mirror guard of my design for left and right motorcycle mirror guards.

FIG. 11 is a bottom, front perspective view thereof.

FIG. 12 is a front view thereof.

FIG. 13 is a rear view thereof.

FIG. 14 is a left-side view thereof.

FIG. 15 is a right-side view thereof.

FIG. 16 is a top view thereof.

FIG. 17 is a bottom view thereof; and,

FIG. 18 is a perspective view thereof mounted on a right motorcycle mirror.

The broken lines in FIGS. 10 and 18 illustrate environment and form no part of the claimed design.
